UNITED STATES PATENT OFFICE

2,066,062

SEPARABLE FASTENER

Sverre Quisling, Madison, Wis., assignor to Hookless Fastener Company, Meadville, Pa., a corporation of Pennsylvania

Application January 12, 1934, Serial No. 706,386

4 Claims. (Cl. 150—3)

My invention relates to separable fasteners and more particularly to the type of fastener disclosed in my prior Patent No. 1,572,808.

The present invention has for its object to improve the patented construction so as to make it more certain in operation; capable of being completely separated throughout its length; and to simplify the construction of the trough member making it easy to attach to the desired article, and improving the working qualities of the fastener.

Other objects and advantages of the invention will be apparent from the following specification.

In the accompanying drawing I have shown for purposes of illustration one embodiment which my invention may assume in practice. In this drawing:

Fig. 1 illustrates a bag equipped with my improved fastener;

Fig. 2 is a view of the fastener in open position;

Fig. 3 is a cross-section on line 3—3 of Fig. 2;

Fig. 4 is a cross-section on line 4—4 of Fig. 1;

Fig. 5 is a cross-section on line 5—5 of Fig. 2;

and

Fig. 6 is a longitudinal section through the initial connecting device.

I have shown my fastening device as applied to a hand bag but it will be understood that it is also useful on many other types of articles such as garment bags and various articles of clothing. The bag comprises a pouch portion 7 with upper edge portions 8 and 9 forming the mouth of the bag. The fastening device comprises generally a trough member 10 secured to the bag by stitching, or any suitable means as indicated in Fig. 3; a flexible hollow casement 11 which may be formed of the bag material as shown in Fig. 2, or formed separately and attached to the bag; and a filling member 12 slidably mounted within the hollow casement. The filling member may comprise a cord with a large diameter portion 13 and a small diameter portion 14. When the small diameter portion is within the casement it will collapse so that it may freely pass through the opening 15 leading to the trough passage 16, which is of larger diameter than the width of the opening.

A feature of the present invention is the outward flare on the mouth 15 forming the guide surfaces 17, 18 which tend to guide the casement and cord into the trough passage without catching. This avoids the difficulty which was sometimes experienced due to the binding or wedg-

ing of the cord and casement against the edge of the trough mouth.

The trough member is preferably made as a rigid one-piece tubular member from metal or celluloid and the opening extends throughout its entire length.

It is desirable to disconnect the sides of the bag completely to allow a wider opening. For this purpose the casement has at one end a rigid portion 19 which is adapted to be manually forced into the trough member at one end. This rigid section and trough member are preferably provided with cooperating shoulders and grooves 20 and 21 so as to align the fastener parts in the proper relation.

It is believed that the operation of the device will now be readily apparent. Assuming that the fastener is open as in Fig. 2, the user will snap together the initial connecting device at one end and then pull the cord member toward the left. The large diameter portion will pass through the rigid tubular section and as it moves through the casement it will pull the casement through the mouth and into the trough passage and will lock the same securely in position when the cord fills the passage. The stop member 22 will limit the closing movement of the cord and the stop member 23 will limit the opening movement. These stops carry a hook and eye arrangement or other suitable connecting device and when fastened together, they constitute a decorative buckle, the cord being used as a carrying handle. In opening the fastener after the cord has been pulled to proper position, a slight pull on the tab 24 will separate the casement from the trough member.

While I have in this specification specifically shown and described one embodiment which my invention may assume in practice, it will be understood that this embodiment is merely for the purposes of illustration and description and that various other forms may be devised within the scope of my invention as defined in the appended claims.

What I claim as my invention is:

1. A fastening device of the character set forth comprising a rigid trough member having a mouth extending throughout the length thereof narrower than the trough passage, a hollow flexible casement member adapted to pass through said mouth into the trough passage, a slidably mounted filling member within said hollow casement, said hollow casement having a rigid tubular section adjacent one end adapted to be manually connected with said trough member to form

an initial connecting means whereby said filling member may be pulled through said casement to lock the same in said trough member.

- 5 2. A fastening device of the character set forth comprising a trough member having a mouth extending throughout the length thereof narrower than the trough passage, a flexible hollow casement and a filling member having a large diameter portion slidable within the casement to pull 10 said casement into the said trough member and lock it in position therein, said filling member having a small diameter portion permitting said casement member to collapse and pass through said mouth, and stop members on the ends of 15 said filling member to limit the sliding movement thereof, said stop members having means for connecting the same together to form an endless loop which provides a handle.
- 20 3. A fastening device of the character set forth, comprising a tubular member of rigid material having a mouth extending along its entire length, the walls of said tubular member adjacent said mouth being bent outwardly to form a flared entrance with smooth guiding walls of substantial 25 area, a flexible casement and a filling cord slid- able within said casement having a large diameter portion and a small diameter portion, a

rigid ferrule attached to said casement at one end adapted to be manually pressed into the mouth of said trough member, said trough member and ferrule having interengaging means to prevent endwise movement after the parts are 5 engaged, said large diameter portion filling said casement when the fastener is closed, to prevent it from passing through said mouth, whereas said small diameter portion when pulled within said casement permits said casement to be 10 withdrawn through said mouth.

4. A fastening device of the character set forth, comprising a one-piece trough member of rigid material having a longitudinally extending passage and opening through a mouth narrower 15 than the diameter of the passage, said mouth extending throughout the length of said trough member, said mouth having outwardly flaring walls 17, 18 integral with the trough member, a flexible hollow casement adapted to pass through 20 said flared mouth opening into said passage, and a flexible member slidably mounted within said casement and having a portion sufficiently large to extend into said casement and fill the trough passage.

25 SVERRE QUISLING.
